FIG. 1.

FIG. 2.

Inventor
Victor Loewenberg
By his Attorney
Maurice Block

UNITED STATES PATENT OFFICE.

VICTOR LOEWENBERG, OF NEW YORK, N. Y.

DESIGN FOR A DOUCHE BED-PAN.

54,856.

Specification for Design. Patented Apr. 13, 1920.

Application filed October 6, 1919. Serial No. 328,918. Term of patent 14 years.

To all whom it may concern:

Be it known that I, VICTOR LOEWENBERG, a citizen of the United States of America, residing at New York city, county and State of New York, have invented a new, original, and ornamental Design for a Douche Bed-Pan, of which the following is a specification, reference being had to the accompanying drawing, forming part hereof, wherein—sign, and Fig. 2 is a central longitudinal section thereof.

I claim:—

The ornamental design for a douche bed-pan as shown.

Signed at New York city, New York, this 3rd day of October, 1919.
